UNITED STATES PATENT OFFICE.

CHARLIE J. BOUSFIELD, OF BAY CITY, MICHIGAN, ASSIGNOR TO THE DELPHEON COMPANY, OF BAY CITY, MICHIGAN, A CORPORATION OF MICHIGAN.

SOUND-CONTROL MECHANISM FOR TALKING-MACHINES.

1,295,083.

Specification of Letters Patent. Patented Feb. 18, 1919.

Application filed October 17, 1916. Serial No. 126,159.

To all whom it may concern:

Be it known that I, CHARLIE J. BOUSFIELD, a citizen of the United States of America, residing at Bay City, in the county 5 of Bay and State of Michigan, have invented certain new and useful Improvements in Sound-Control Mechanisms for Talking-Machines, of which the following is a specification.

10 This invention relates to sound control mechanisms for talking machines.

One object of the invention is to produce a simple and economical device for regulating and controlling the volume of sound 15 emitted from the tone horn of a talking machine.

Another object is to provide a device of this character that can be controlled during playing, by the operator at any distance 20 from the machine.

A further object resides in the provision of a tone horn of a talking machine with a valve or muffler for controlling the volume 25 of sound emitted therefrom and provided with means for operating the same.

With the above and other objects in view, the present invention consists in the combination and arrangement of parts hereinafter more fully described, illustrated in the 30 accompanying drawings, and particularly pointed out in the appended claim, it being understood that changes may be made in the form, size, proportion and minor details without departing from the spirit or sacrificing any of the advantages of the invention.

In the drawings:—

Figure 1 is a sectional view of a cabinet talking machine with the device positioned 40 therein.

Fig. 2 is an enlarged plan view of the device.

Fig. 3 is an enlarged side elevation of the device.

45 In the drawings 1 indicates a cabinet talking machine of the type now in general use. The usual compartment 2 is provided in said cabinet, through which the tone horn 3 extends. The tone horn is provided intermediate 50 its length with a valve or muffler 4 rigidly secured to an arbor 5 mounted to oscillate in suitable bearings formed in the tone horn. The arbor 5 is oscillated through the instrumentality of an arm 6 secured to

the arbor 5 at a point located exteriorly of 55 the horn 3.

Within the compartment 2 is located a flat bar 7 slidably mounted on a bracket 8 fastened to the interior wall of the cabinet 1. One end of said bar 7 is provided with a 60 series of notches 9 adapted to engage a pin 10 fixed in the side of the cabinet 1 adjacent the bracket 8.

A lever 12 is pivoted to the side of the cabinet 1 by means of the pin 11, but spaced 65 therefrom, and one end of which is pivoted to the end of the bar 7 by means of the pivot pin 13. The lever 12 is spaced from the bar 7 by means of said pivot pin 13. The opposite end of the lever 12 is pivoted to a second 70 lever 14 as shown at 15, and this second lever 14 has its opposite end pivoted to the arm 6, by means of the pin 16.

A spring 17 has one end attached to a pin 16, while its opposite end is attached to the 75 side of the cabinet 1. This spring has a tendency to hold the valve or muffler 4 in its closed position.

The bar 7 is adapted to be moved by means of a cord or rope 18 attached to the 80 free end of the bar and terminating in a tassel 18' which extends through an aperture 19 in the side of the cabinet 1 to the interior thereof.

In order to allow operation of the bar 7 85 by a person sitting at a distance from the cabinet, an auxiliary cord 20 is provided, which cord is adapted to be fastened to the end of the cord or rope 18 by a snap fastener adapted to hook into a ring concealed in 90 the tassel 18'.

From the foregoing it will be apparent that it is only necessary to pull outwardly 95 on the rope or cord 18 to open the valve or muffler to any degree desired, thus by pulling outwardly and releasing the cord 20, which will open and close the muffler or valve 4, (through instrumentality of the bar 7, lever 12 and 14 and arm 6) the operator can enunciate the music as the record is being played. If a certain volume of tone is desired, the operator by elevating the auxiliary cord 20, (as shown in dotted lines in Fig. 3), hooks one of the notches 9 in the bar 7 over the pin 10, thus holding the valve or 100 muffler 4 in any desired position, from which it can be disengaged by pulling outwardly 105 on the string 20.

By providing the auxiliary cord 20 it will be apparent that the operator of the talking machine may sit any desired distance or angle in front of same, and control the volume 5 of sound emitted from the tone horn.

What I claim, is:—

In a talking machine provided with a tone modifier normally held closed, means for operating such modifier from a distant point 10 and holding the same in an adjusted position, consisting of a member mounted to re-

ceive both a pivotal and a longitudinal movement and having a series of teeth in its length, an element to co-act with the teeth to hold the member in the adjusted position, 15 and a flexible operating member extending from the pivotal and longitudinally movable member to admit of the two-fold movement being imparted thereto from any required point distant from the machine. 20

In testimony whereof I affix my signature.
CHARLIE J. BOUSFIELD.
